UNITED STATES PATENT OFFICE.

RASMUS P. HANSEN, OF ERINDSLEV SOGN, DENMARK.

VALVE MECHANISM FOR EXPLOSIVE-ENGINES.

SPECIFICATION forming part of Letters Patent No. 706,932, dated August 12, 1902.

Application filed May 4, 1899. Serial No. 715,671. (No model.)

To all whom it may concern:

Be it known that I, RASMUS PEDER HANSEN, a subject of the King of Denmark, and a resident of Erindslev Sogn, Denmark, have invented certain new and useful Improvements 5 in Valve Mechanism for Explosive-Engines, of which the following is a specification.

My invention relates to a device for moving the valves and regulating the fuel-feed in 10 four-cycle gas and petroleum motors.

My invention is illustrated in the accompanying drawings, in which—

Figure 1 is a front view of the motor-cylinder with the valve-operating mechanism 15 with a partial section through the valve-chamber, while Figs. 2 and 3 illustrate two separate positions of the valve-operating mechanism and of the regulator.

A is the motor-cylinder, which is closed 20 above by a lid C.

From the piston of the motor the movement is transmitted in the usual manner by a sliding rod to the crank-shaft. (Not shown.) On the crank-shaft is keyed an eccentric disk, 25 (not shown,) to the strap of which the one extremity of the rod a is secured. The other extremity of this rod a is connected with the rod b, which is guided in N, and at the upper extremity of which is linked a pivoted rod d, 30 which stands vertically in normal position and is pressed by a spring e against a stationary projection f. A button or knob g is screwed fast on the valve-spindle h, Fig. 3, said knob being provided with two notches 35 g' and g'', Fig. 2. A lever-bar I', having a notch i' on one arm, is pivoted on the stud i and is kept in normal position by the spring l against the projection k.

m is another lever-arm pivoted around the 40 stud m² and having an arm m³ directed vertically downward and also provided with a notch m', which serves to catch the arm i' on the lever-arm I'. The lever-arm m is connected with the arm i³ of this lever by the 45 spring l.

n is a projection set on the head g of the valve-spindle, which actuates the lever-arm n', which moves the petroleum-pump n², Fig. 1.

50 The regulator O, Figs. 2 and 3, is pivoted on the stud o and is weighted at the one arm by a weight o', while its other arm possesses

a slanting, smooth, and reduced end o². The regulator is held at its resting position against the detent o³ by means of a spring o⁴. The 55 pivot o is fixed on the arm p', which carries besides the detent-pin o³ another pin p², Fig. 1, on which the spring o⁴ is fixed. The arm p' is pivoted around the pin p, Fig. 1, and is actuated by a projection on the rod b. 60

A lever R pivots around the stud r, Fig. 3, and is pressed at its resting position against the stop r³ by means of the spring r⁴, Fig. 2. On the boss of this pivoted lever is a projection r⁵, which carries another small pin for 65 the purpose of pressing against another spring r⁶, also arranged on the boss of the lever. The lever R has a small notch r', which lies opposite the pointed extremity o² of the regulator-arm. 70

On the pin r, but behind the lever R, is a block s, tapering upwardly, which carries a pin s' for fastening the spring r⁶. The projections f, k, and r³, the pivots i, m³, and r, and the spring r⁴ are all secured to a plate M, 75 arranged on the cylinder A, Fig. 1, while the guide-bearing N for the rod b and the petroleum-pump n² are fixed on a plate arranged on the block B.

In explanation of the operation of the arrangement the following describes one of the working periods of the motor, which, as usual in this kind of machines, comprises during two revolutions afflux, compression, ignition, expansion, and eduction. The admission- 80 valve I, Fig. 1, acts automatically, and as its spring is weaker than the one of the eduction-valve it can be opened by the pressure of the atmosphere during the downward stroke of the piston. The eccentric which moves 85 the eduction-valve stands about ninety degrees ahead of the crank, (calculated according to the rotation direction.) When the piston is moved downward, the eccentric has reached the lowest dead-point place at the 90 middle of the piston-stroke and will thereafter move upward again during the further downward stroke of the piston. When the piston moves up again after having reached the lowest dead-center point, the rod d, which 95 is now also moved upward by the eccentric, must be prevented from striking against the head g, and thereby opening the eduction-valve. This object is obtained by the rod d 100

striking on the notch i' of the lever I' when the parts are in the position shown in Fig. 1 and guiding the latter into the position represented in Fig. 2, where it is held fast in the lever m by the notch m' . In the further operation of the machine the explosion takes place at the uppermost dead-point and the expansion takes place thereafter during the downward stroke of the piston. At the middle of the expansion-stroke the eccentric is again at the lowest dead-point and thereafter proceeds upward. The length of the rods d and g is measured in such a manner that the rod d strikes against the notch g' in the head g at the moment when the piston is at the lowest dead-point. The head is raised again and lifts the rod g , and thereby the eduction-valve K , Fig. 1, which now remains open during the whole eduction-stroke. Simultaneously with the opening of the valve the rod d presses upon the arm m^3 of the lever m and raises the same upward, so that the arm i^2 is released, whereafter the lever I' slides back during the downward slide of the rod d and resumes the position shown in Fig. 1 at the close of the exhaust-stroke. The working period is now accomplished. By the shoulder n and the rod n' the piston of the petroleum-pump receives a downward movement during the opening of the eduction-valve, so that the petroleum is driven upward through the tube n^3 into a vaporizer arranged in the lid of the cylinder. The pump-piston is guided back by the spring n^4 and simultaneously sucks up petroleum. The regulator acts in such a manner that when the speed of the machine becomes too great it prevents entirely the induction of the fuel into the cylinder. This is accomplished in the following manner: The regulator-spring o^4 is arranged in such a manner that the point o^2 of the regulator-arm passes by the notch r' of the lever R , Fig. 2, during the upstroke at normal operation. When the speed becomes too great, the weight o' , arranged on the one arm of the regulator, will tend in the upstroke to remain in its original position. Thereby the resistance of the spring is overcome and the regulator is turned in such a manner that its point o^2 engages in the notch r' and raises the lever R . If this takes place during the compression-stroke, Fig. 2, which occurs but rarely, as the speed of the engine is smaller at that period, the block s is pressed against the head g by the shoulder r^5 and spring r^6 , and as a consequence the spring will simply yield still more. Should this occur, however, during

the eduction-stroke, the block s will engage the notch g^2 and will press the head g upward while the valve K is kept open, Fig. 3. Instead of sucking up a charge the piston will now suck up through the opened eduction-valve K the combustion products expelled at the latter stroke. At the next eduction-stroke the block s will be released. As the petroleum-pump is moved by the spindle of the eduction-valve the spindle omits a piston-stroke every time that the machine skips an explosion.

I claim—

1. In an explosive-motor, the combination with the cylinder, the eduction and inlet valves, a rod operated from the crank-shaft of the motor making two rearward reciprocations to each opening of the eduction-valve, a petroleum-pump, an operating-lever therefor, a head carried by the stem of the eduction-valve, means carried by the head coacting with the lever to operate the same as said head is raised, means carried by said rod for lifting said head, and speed-regulating mechanism operated by said reciprocating rod, adapted to coact with said head independent of said means carried by the rod, substantially as described.

2. The combination in an explosive-motor with the eduction-valve, and stem carrying the same, and a reciprocating rod, of a head secured to the valve-stem, means carried by the reciprocating rod coacting therewith to lift the same to open said valve, means for returning the valve and speed-regulating mechanism independent of the means carried by the rod and operated from said rod also adapted to engage said head to prevent the return of the valve, substantially as described.

3. The combination in an explosive-motor, with the eduction-valve and stem carrying the same and the reciprocating rod of a head carried by said stem, an arm oscillated by the rod, a governor-arm pivoted thereto, a second arm adapted to be engaged by the governor-arm whereby the same is tilted on one stroke of the piston-rod, and a block yieldingly connected to said arm adapted to coact with the head on the valve-stem, substantially as described.

In witness whereof I have hereunto set my hand in presence of two witnesses.

R. P. HANSEN.
